UNITED STATES PATENT OFFICE.

ALBION HENRY LOWELL, OF MANCHESTER, NEW HAMPSHIRE.

DESIGN FOR SHELF-BRACKET.

Specification forming part of Design No. 7,467, dated June 2, 1874; application filed April 17, 1874.
[Term of Patent 3½ years.]

To all whom it may concern:

Be it known that I, ALBION HENRY LOWELL, of Manchester, Hillsborough county, in the State of New Hampshire, have invented a Design for Shelf-Bracket, of which the following is a specification:

The nature of my design is fully represented in the accompanying engraved illustration, to which reference is made.

A is the vertical, and B the horizontal, part of the bracket, which are braced by the ornamental scroll-work C C, connected to the ring D, which surrounds the open star-frame E, with a scalloped opening in the center, mak-

ing a strong, beautiful, and highly-ornamental bracket for supporting shelves and other purposes.

What I claim as my invention or production is—

The design for a bracket, consisting of the horizontal and vertical parts A B, scroll-work C C, ring D, and open-work star E, with the opening scalloped in the center.

ALBION HENRY LOWELL.
